Patented Apr. 17, 1917.

UNITED STATES PATENT OFFICE.

GEORGE W. DAVENPORT AND LOUIS J. BURKHIM, OF GAINESVILLE, FLORIDA.

AUTOMATIC PIANO-PLAYER.

1,222,738.

Specification of Letters Patent. Patented Apr. 17, 1917.

Application filed September 22, 1915. Serial No. 51,967.

To all whom it may concern:

Be it known that we, GEORGE W. DAVENPORT and LOUIS J. BURKHIM, citizens of the United States, residing at Gainesville, in the county of Alachua and State of Florida, have invented certain new and useful Improvements in Automatic Piano-Players, of which the following is a specification.

Our invention consists in a new and useful improvement in automatic piano players, adapted to be applied to the ordinary type of upright pianos, without alteration to the piano. It comprises a combination of a plurality of pneumatic control valves of novel construction arranged in a player stack composed of two layers and adapted to operate in conjunction with the usual devices of an automatic piano player, such as a spool box, tracker bar and pneumatic generator. The invention further consists in the details of construction hereinafter pointed out.

In the drawings:

Figure 1 is a front view of the device, showing an end of the two layers of the stack in position in a piano body.

Fig. 2 is a front view of a portion of the upper layer of the stack, partly in section, showing the structure of the control valves in the layer.

Fig. 3 is a cross-sectional view, through the center of one of the control valves in the upper layer of the stack.

The two layers, A and B, in the player stack extend laterally the length of the keyboard of the piano to which the player is adapted and are held in position in the space immediately between the keys and the wippen of the piano action, by means of two longitudinal iron bars, A' and B', which extend from side to side of the piano body.

Each layer consists of a series of pneumatic control valves so arranged as to control each its own power bellows adapted to operate its actuating finger situated beneath the wippen of the piano action for each alternate hammer in the piano. The valves in the two layers, thus operating, control all the hammers.

Each layer is composed of three superimposed wooden plates, C, D and E, extending the entire length of the stack, to the front of which is affixed a front plate, F, of glass, to form an air-tight cover, permitting inspection of the construction within the

layer. Each end of the layer is closed by an end plate, G. The construction of the three superimposed wooden plates, C, D and E, comprises the novel form of pneumatic control valves. It is to be understood that in the following description the construction in each layer is duplicated for each valve in the series.

In the top plate, C, of the series of three, there is situated near the outer edge of the plate a circular orifice 1, in which is set a valve seat 2, composed of a circular collar of glass, porcelain or other suitable non-corrosive material, adapted to fit into the orifice 1 with an air-tight joint. Affixed to the top of the plate C and projecting over the center of the orifice 1 is a wooden finger 3, provided with a circular orifice 4, concentric with the orifice 1, to serve as a guide for the valve stem.

In the top of the second or middle plate, D, there is a rectangular recess 5, extending from the outer edge of the plate D through approximately one half the width of the plate and in depth approximately one quarter of the thickness of the plate D. From the inner side of this recess 5, there extends a circular air duct 6, curving inwardly and downwardly through the inner end of the plate D and passing out at the bottom of the plate D. Situated in the bottom of the recess 5 is an orifice 7, in depth approximately one quarter of the thickness of the plate D, having the same diameter and concentric with the orifice 1 in the top plate C. In this orifice 7, is set a valve seat 8, composed of a circular collar of glass, porcelain or other suitable non-corrosive material, adapted to fit into the orifice 7 with an air-tight joint. Beneath and projecting below the center of the orifice 7, there is a wooden finger 9 provided with a circular orifice 10, concentric with the orifices 7, 1 and 4, to serve as a guide for the valve stem.

Beneath the orifice 7, the plate D is cut away from its outer edge through approximately three quarters of its width and the remaining half of its thickness and throughout its entire length, to form the vacuum chamber 11. Thus it will be seen that this vacuum chamber 11 extends the entire length of each layer and is connected through the orifices 7 in the plate D with each of the control valves. The vacuum chamber 11 is closed at each end by the end plate G, and it is

connected, at one end by a tube 11' with the vacuum bellows of the pneumatic system of the player.

In the top of the third or bottom plate E, 5 which is the diaphragm board, there is a circular recess 12, situated near the outer edge of the plate E. This circular recess 12 has a depth approximately one half of the thickness of the plate E and a diameter approximately twice the diameter of the orifices 1 and 7, and is so situated that it is 10 concentric with the orifices 10, 7, 1 and 4. Forming an air-tight covering of the top of this recess 12, is a skin diaphragm 13, adapted 15 to be expanded and contracted by the air-pressure in the recess 12. Passing from the middle of the inner side of the recess 12, through the center of the plate E and opening through the inner side of the plate E, is 20 a circular air duct 14, to connect the recess 12 with the tracker bar of the player. In the end 15 of this air duct 14, adjacent to the recess 12, there is located a minute air duct 16, through the top of the plate E, into the 25 vacuum chamber 11, to serve as the "bleed" valve. Passing from top to bottom through the inner end of the plate E, there is an air duct 17, so situated as to communicate with the opening of the air duct 6 in the bottom 30 of the middle plate D, and opening through the bottom of the bottom plate E into the power bellows 18.

The valve stem 19 is composed of wood and is of suitable length and diameter to 35 fit in the described construction in the manner set forth. The lower end of the stem 19 has an enlarged, pear-shaped portion 20, which rests on the center of the skin diaphragm 13 covering the recess 12 in the bottom 40 plate E. Passing upwardly through the vacuum chamber 11, held vertical therein by the orifice 10 in the guide finger 9, the stem extends through the valve seat 8, the recess 5, the valve seat 2, and has its upper end 45 passing through the orifice 4 in the guide finger 3 above the valve seat 2. Passing horizontally through the center of the stem 19, at the point where the stem 19 passes through the valve seat 8, there is a metal 50 pin 22 which projects slightly on either side of the stem 19. Resting upon these projections and surrounding the stem 19, there is a circular lead washer 23. Above this washer

23, surrounding the stem 19, there is a circular leather disk 24, above which there is 55 a felt disk 25, a fiber disk 26, a second felt disk 25' and a second leather disk 24'. Both leather disks 24 and 24' and both felt disks 25 and 25' are adhesively connected to the stem 19. The fiber disk 26, is provided with 60 a central orifice 27, slightly larger than the diameter of the stem 19. Each of these disks is adhesively connected with its adjoining disks. The diameter of these disks is slightly greater than that of the orifices 1 and 7. These disks are so situated on the valve stem 19, in the recess 5, that when the skin diaphragm 13, covering the recess 12, is contracted by the reduction of the air-pressure in the recess 12, depressing the 70 valve stem 19, the lower leather disk 24 rests upon the upper edge 28 of the valve seat 8 in the bottom of the recess 5, with an air-tight joint, and when the skin diaphragm 13 is expanded by an increase of the air-pressure in the recess 12, elevating the valve stem 19, the upper leather disk 24' is in contact with the lower edge 29 of the valve seat 2, so as to form an air-tight joint.

Having described our invention, what we 80 claim is:

The combination in a pneumatic control valve of a piano player, of a skin diaphragm forming the base rest for the valve stem, a valve stem composed of wood, having an 85 enlarged base portion and provided with a transverse pin and a circular washer of lead, two leather, and two felt disks surrounding the valve stem and adhesively connected thereto, a fiber disk between the two 90 felt disks and adhesively connected thereto, provided with a central orifice of slightly greater diameter than the diameter of the valve stem, two valve seats composed of non-corrosive material and situated above and 95 below the two leather disks, and two guide fingers of wood for the valve stem, one above and one below the two valve seats.

In testimony whereof we affix our signatures in presence of two witnesses.

GEORGE W. DAVENPORT.
LOUIS J. BURKHIM.
